UNITED STATES PATENT OFFICE.

JOHN H. CORNELISON, OF ST. LOUIS, MISSOURI.

SWINGING WINDOW-SCREEN.

1,028,679.

Specification of Letters Patent. Patented June 4, 1912.

Application filed April 15, 1909. Serial No. 489,977.

To all whom it may concern:

Be it known that I, JOHN H. CORNÉLISON, a citizen of the United States, residing at the city of St. Louis, in the State of Missouri, have invented a certain new and useful Swinging Window-Screen, of which the following is such a full, clear, and exact description as will enable any one skilled in the art to which it appertains to make and use the same, reference being had to the accompanying drawings, forming part of this specification.

The object of my invention is to produce a swinging window screen which will be as simple as possible in construction and hence will not only be easy to manufacture and low in cost but which will also be reliable in action and not likely to get out of order.

A further object of my invention is so to construct a screen that it may be made in half lengths and reversed so as to be applied to either the lower or the upper half of the window frame.

In the accompanying drawings, which illustrate some forms of screen made in accordance with my invention, Figure 1 is a vertical central section of a window frame provided with my preferred form of screen; Fig. 2 is a slightly enlarged view of the upper part of Fig. 1 showing the screen reversed; Fig. 3 is an enlarged section on the line 3—3 of Fig. 1; Fig. 4 is a view similar to Fig. 1 but showing the full length screen; Fig. 5 is an enlarged view of the upper portion of Fig. 4; Fig. 6 is a section on the line 6—6 of Fig. 4; Fig. 7 is an enlarged view showing a modification in which the screen is placed between the blind parting strips; Fig. 8 is a view showing means for yieldingly supporting the screen without springs; Fig. 9 is a section on the line 9—9 of Fig. 7, and Fig. 10 is a section through the lower part of the screen showing a modification.

Like marks of reference refer to similar parts in the several views of the drawings.

15 is the window frame which is provided with a lower sash 16 sliding between guide strips 17 and 18 and an upper sash 19 sliding between the guide strip 18 and the blind parting strips 20.

In my preferred form of screen, as shown in Figs. 1, 2 and 3, the screen 21 is arranged to bear against blind parting strips 20. The end of the screen 21 which is at the top when the screen is in the position

shown in Fig. 1 is provided with a filling strip 22 which is of greater thickness than the remainder of the screen and this filling strip 22 is provided with bearings 23 adapted to engage with pins 24 in the blind parting strips 20 at a point slightly above the middle of the window frame. In order to hold the screen in position against the pins 24 springs 25 are provided, one end of each of said springs being secured to the screen 21 at its central point and the other being adapted to engage with a hook 26 in the blind parting strip adjacent to the bearing pins 24. It will be evident that the tension of the spring 25 will hold the screen in position against these bearing pins and at the same time allow the lower end of the screen to be swung outwardly.

In order to allow for the reversal of the screen so that it may be used at the upper part of the window frame, I place adjacent to the transverse blind parting strip a projection or strip 27 leaving a recess 28 adapted to receive the end of the screen opposite to the filling strip 22, as is shown in Fig. 2. Adjacent to these recesses 28 is a hook 29 adapted to be engaged with the end of the spring 25 so that the same spring may be used to hold the screen in place in either position. As the lower sash of a window is somewhat longer than the upper, the pins 24 will come in such a position as to miss the filling strip 22 when the screen is in its upper position, as shown in Fig. 2 of the drawings.

In Figs. 4, 5 and 6 I have shown a modification in which a screen 30 is made the entire length of the window frame and hence can not be reversed. It is held in position in substantially the same manner as the screen 21 when in the position shown in Fig. 2. In this modification, however, it is not necessary to have a spring which extends to the central portion of the screen as the spring is not reversed. Consequently I use a short spring 31 as shown in detail in Fig. 5 of the drawings. On account of the length of the screen 30 it is desirable to have means for securing the lower end of it in position when it is not desired to open it and consequently I provide it with a retaining hook 32, as shown in Fig. 6.

In Fig. 7 of the drawings I have shown a modification in which a screen 33, in place of fitting against the blind parting strips 20, is arranged between such strips so that

a blind may be used in conjunction with the screen. In order to allow this, apertures 34 are formed in the upper rail of the screen and through these apertures pass 5 wires 35 attached to springs 36 which are in turn secured to the sides of the screen. The upper end of the wires 35 engage with hooks 37 in recesses 38 communicating with the apertures 34. In this way it is evident 10 that a screen may be placed between blind parting strips as shown in Fig. 7 and Fig. 9.

In Fig. 8 I have shown a modification in which the yielding suspension of the screen is obtained without the use of springs. In 15 this modification the screen 30 is beveled at its upper end as shown at 40 and is provided with a pin 41 adapted to engage with a suitable aperture in the upper portion of the window frame. As will be seen from 20 Fig. 8 of the drawings, the screen is made slightly shorter in this construction so that it may move upwardly as it is swung outwardly at the bottom. In place of the spring 31 I use a wire 42 secured to the 25 screen and to the hook 29. It will be evident that in this construction the weight of the screen itself furnishes the yielding means for holding it in position and that the pin 41 retains it against accidental 30 placement.

In Fig. 10 I have shown a modification which is useful in connection with the form of screen shown in Fig. 7 which lies between the blind parting strips. In order to 35 allow for the fastening of the blinds 43 the lower portion of this screen is cut away at 44 so as to admit access to the fastening hook 45 of the blind. This cut away portion 44 is covered by a board 46 which is secured in 40 position by means of pins 47 in the bottom of the window frame and detachable hooks 48.

Having fully described my invention, what I claim as new and desire to secure by 45 Letters Patent of the United States is:

1. In combination with a window frame, a swinging screen, longitudinally extensible springs permanently fastened at corresponding ends to the inner face of the screen and 50 their other ends pivotally connected to and readily detached from the frame, allowing the entire screen to be moved away from the frame and held in parallel or oblique planes thereto, said springs serving, when under 55 tension, to hold one edge of the screen in revoluble contact with the frame and normally holding the inner face of the screen yieldingly against the frame, as set forth.

2. In combination with a window frame, a 60 swinging screen, longitudinally extensible springs loosely connected at corresponding ends to the inner face of the screen and to said frame, allowing the entire screen to be moved away from the frame and held in 65 parallel or oblique planes thereto, said

springs serving, when under tension, to hold one edge of the screen revolubly in contact with the frame and normally holding the inner face of the screen yieldingly against the frame, as set forth.

3. The combination with a window frame, provided with a projection at its upper end and with bearing pins, of a screen, one end of which is adapted to engage with said projection when the screen is in one position and the other end of which is adapted to engage with said pins when the screen is in another position.

4. The combination with a window frame provided with a projection at its upper end and with bearing pins, of a screen, one end of which is adapted to engage with said projection when the screen is in one position and the other end of which is adapted to engage with said pins when the said screen is in another position, and yielding means for holding said screen in position.

5. The combination with a window frame, provided with a projection at its upper end and with bearing pins, of a screen, one end of which is adapted to engage with said projection when the screen is in one position and the other end of which is adapted to engage with said pins when the screen is in another position, and spring means for yieldingly holding said screen in position.

6. The combination with a window frame provided at its upper end with a projection upon the frame at one end and at the intermediate point with bearing pins, of a screen, one end of which is adapted to engage with said projection when the screen is in one position and the other end of which is adapted to engage with said pins when the screen is in another position, and a spring secured at 100 one end to said screen and adapted to be secured at the other end adjacent both to said projection and to said pins.

7. The combination with a window frame provided with a projection at its upper end and with bearing pins, of a screen, one end of which is adapted to engage with said projection when the screen is in one position and the other end of which is adapted to engage with said pins when the screen is in 115 another position, and a spring secured at one end near the center of said screen and adapted to be secured at the other end adjacent to both said projection and to said pins.

8. The combination with a window frame provided at its upper end with a projection and at a point above its center with bearing pins, of a screen of more than half the length of said frame, one end of said screen being adapted to engage with said projection and the other with said bearing pins.

9. The combination with a window frame provided at its upper end with a projection and at a point above its center with bearing pins, of a screen of more than half the 130

- length of said frame, one end of said screen being adapted to engage with said projection and the other being provided with a filling piece of a thickness approximately equal 5 to the width of the outer parting strip of the window frame and adapted to engage with said pins, and yielding means for securing said screen in both its upper and lower position.
- 10 10. The combination with a window frame provided at its upper end with a projection and at a point above its center with bearing pins, of a screen of more than half the length of said frame, one end of said screen being 15 adapted to engage with said projection and
- the other being provided with a filling piece of greater thickness than the remainder of the screen and adapted to engage with said pins, and a spring secured at one end to the center of said screen and adapted to be secured 20 at the other end adjacent both to said projection and said pins.

In testimony whereof I have hereunto set my hand and affixed my seal in the presence of the two subscribing witnesses.

JOHN H. CORNELISON. [L. S.]
